UNITED STATES PATENT OFFICE

JOHN SIMPSON, OF FAIRBURY, NEBRASKA, ASSIGNOR TO FAIRBURY WINDMILL COMPANY, OF FAIRBURY, NEBRASKA, A CORPORATION OF NEBRASKA

PUMP-ROD SWIVEL FOR WINDMILLS

Application filed July 9, 1928. Serial No. 291,169.

My invention relates to windmills and particularly to the structure and arrangement of the pump rod swivel.

Its primary object is the provision of an arrangement for extending the principle of automatic lubrication to the pump rod swivel.

Another object is the provision of a structure whereby the pump rod swivel may be subjected to the action of the lubricant which is splashed or carried by the action of the gears and pitmen of the windmill.

Still another object is the positioning of the windmill swivel under the cowl of the windmill so that it will not be affected by dust, rain or other atmospheric conditions.

Another object is the provision of a pump rod swivel mount which is easily accessible for repairs.

Still another object is the provision of a swivel arrangement which will function freely and easily and which is not liable to get out of repair.

Having in view these objects and others which will be pointed out in the following description, I will now refer to the drawings, in which

Figure 1 is a view in front elevation of the windmill head with parts of the cowl and oil reservoir broken away to disclose the position and structure of the novel pump rod swivel.

Figure 2 is a view in front elevation of the pump rod swivel.

Figure 3 is a view in side elevation of the pump rod swivel.

In common with nearly all windmills the windmill shown in the drawings includes a wheel shaft 10 with means for lubricating the pitmen 11 to actuate the pump rod 12. In the present instance the shaft 10 is connected to pinions (not shown) which mesh with the helical gears 13 having the pitmen 11 connected eccentrically thereto. The crosshead connecting the pitmen 11 at their upper ends travels in the guide shoes 14 for maintaining the vertical movement of the crosshead. The helical gears 13 are partially immersed in an oil bath contained within the oil receptacle 15 and the oil in

the oil bath is carried upwardly to the crosshead by the action of the gearing and pitmen. On the oil receptacle 15 is seated the cowl 16 which encloses all of the working parts of the windmill to exclude rain, wind, snow and dust. The windmill head is rotatably mounted on a vertical mast projecting upwardly from the tower 17. All of the parts thus far described are shown in greater detail and are more fully explained in Patent No. 1,611,114, granted to the Fairbury Windmill Company as the assignee of Clarence G. Henney, on December 14, 1926.

In all prior constructions so far as I am aware, the pump rod 12 is rigidly connected to the crosshead. Since the windmill head is frequently turned on its vertical axis through the action of the wind, it is necessary to provide a swivel in the pump rod to prevent the twisting of the pump rod when the windmill head is turned. So far as I am aware the swivel is always positioned in that portion of the pump rod below the windmill head where it is exposed at all times to the elements. This swivel is relatively inaccessible and it seldom receives any attention with the result that it is very apt to get out of repair because of insufficient lubrication. It is apparent, however, that a swivel which is subjected to continuous movement, such as that in the pump rod of a windmill, must be adequately lubricated both to reduce friction and to prevent the undue wearing of parts.

The parts associated with the pump rod swivel include a sleeve 18 which is adapted to embrace the rod connecting the pitmen 11 at their upper extremities. The sleeve 18 is provided with flanged ends 19 and with a depending U-shaped member 20 and also with a lateral plate-like projection 21. The parts 18 to 21 inclusive are all of integral construction and they are preferably made from a light weight metal or alloy. Seated against the lower portion of the U-shaped member 20 is a clamping plate 22 which is secured to the member 20 by means of bolts 23 or the like passing through registering apertures in the U-shaped portion 20 and in the clamp plate 22. The U-shaped member 20 and the

clamping plate 22 are each provided with a semicylindrical vertical channel, the two channels registering in the assembled device to provide a vertical aperture. The parts 20 and 22 are further held together and against displacement by means of a V-shaped ridge 24 which is seated in a V-shaped groove 25 in the member 20 all as shown in Figure 3. The cylindrical aperture formed between the members 20 and 22 is slightly greater in diameter than the diameter of the pump rod 12 so that free swivel action is possible for the pump rod. In the downward movement of the pump rod under the action of the pitmen 15 11 the upper end of the pump rod abuts against the projection 21. The pump rod is also provided with a nut 26 or similar projection for preventing the moving away of the crosshead from the pump rod during the upward movement of the pitmen.

The lubrication of the windmill is entirely automatic. The helical gearing 13 is partly immersed in the lubricant, the wrist pin to which the pitman is attached being forced to 25 dip into the lubricant. The lubricant then creeps upwardly on both the guide shoes and the pitmen during the reciprocation of the pitmen and it finally creeps over the crosshead. As described in the aforementioned 30 patent additional means are provided for positively forcing the lubricant to travel upwardly on the guide shoes and on the pitmen. The prior arrangement as well as all other prior arrangements have provided for the 35 automatic lubrication of all working parts of the windmill except the swivel of the pump rod.

By positioning the swivel of the pump rod in the manner shown in the drawings, the lubricant which creeps over the crosshead is carried into the swivel of the pump rod, this action being facilitated by the reciprocation of the pitmen and of the pump rod. Due to the lubrication which it receives the parts of 45 the swivel will not become gummed or clogged as they would be if heavy grease were used to lubricate a swivel which is entirely exposed to the air and where the lubricant was allowed to dry out and become filled with dust 50 and sand. Due to the continuous lubrication of the swivel and the flushing of the swivel with lubricant, sand and grit are not permitted to accumulate in the swivel and the parts are not given a chance to become rusty. 55 The swivel not only requires less attention than the prior swivels but its life is materially increased because of the thorough lubrication and because of the protection afforded 60 by the cowl 16.

Having thus described my invention in such full, clear, and exact terms that its construction and operation will be readily understood by other skilled in the art to which it pertains, what I claim as new and desire to se-

cure by Letters Patent of the United States is:

1. Automatically operable means for lubricating the pump rod swivel of a windmill, said means including an oil bath in the windmill head, mechanism in the windmill for converting rotary motion into rectilinear reciprocating motion, said mechanism including a pitman crosshead and a crosshead guide, the lower portion of said mechanism being immersed in the oil of said oil bath whereby the oil is conveyed by splashing and creeping to all parts of said crosshead, and a swivel on said crosshead for the pump rod of the windmill lubricated by the oil conveyed to the crosshead. 70

2. Automatically operable means for lubricating the pump rod swivel of a windmill, said means including a windmill head having therein an oil bath and mechanism for converting rotary motion into rectilinear reciprocating motion in a vertical direction, the lower portion of said mechanism being immersed in the oil of said oil bath whereby lubricant is conveyed to all parts of said mechanism by splashing and creeping during the movements thereof, said mechanism including a pump rod, a crosshead and a crosshead guide, and a swivel connection between said crosshead and the upper extremity of said pump rod lubricated by the oil conveyed to the crosshead. 85

In testimony whereof I affix my signature.
JOHN SIMPSON.
